UNITED STATES PATENT OFFICE.

EMIL G. SAUER, OF RICHMOND HILL, NEW YORK, ASSIGNOR TO BIGELOW HARTFORD CARPET COMPANY, A CORPORATION OF MASSACHUSETTS.

DESIGN FOR A RUG.

46,847.

Specification for Design.

Patented Jan. 5, 1915.

Application filed November 17, 1914. Serial No. 872,662. Term of patent 3½ years.

To all whom it may concern:

Be it known that I, EMIL G. SAUER, a citizen of the United States, residing in Richmond Hill, in the county of Queens and State of New York, have invented a new, original, and ornamental Design for a Rug of Carpet Sizes, of which the following is a specification, reference being had to the accompanying drawing, forming part thereof.

The drawing illustrates a portion of a rug showing my new design.

I claim:

The ornamental design for a rug, substantially as shown.

EMIL G. SAUER.

Witnesses:

DAVID G. BARRY,
LLOYD E. KENNEDY.
